UNITED STATES PATENT OFFICE

156,127

DESIGN FOR A HALTER

Adam L. Kinskie, Morristown, Tenn.

Application November 17, 1948, Serial No. 149,675

Term of patent 7 years

(Cl. D38—6)

To all whom it may concern:

Be it known that I, Adam L. Kinskie, a citizen of the United States, residing at Morristown, in the county of Hamblen and State of Tennessee, have invented a new, original, and ornamental Design for Halters, of which the following is a specification, reference being had to the accompanying drawing, forming part thereof.

In the drawing:

Fig. 1 is a front view of a halter, showing my new design.

Fig. 2 is a side elevational view of the halter with the chain and holding strap shown in broken lines in Fig. 1 omitted therefrom.

The essential features of my design for a halter reside in the parts shown in full lines.

I claim:

The ornamental design for a halter, as shown and described.

ADAM L. KINSKIE.
